CLAIM

The ornamental design for an air fryer, as shown and described.

DESCRIPTION

FIG. 1 is a front perspective view of an air fryer of the present disclosure showing our design;

FIG. 2 is a rear perspective view of the air fryer shown in FIG. 1;

FIG. 3 is a front elevational view of the air fryer shown in FIG. 1;

FIG. 4 is a rear elevational view of the air fryer shown in FIG. 1;

FIG. 5 is a left-side elevational view of the air fryer shown in FIG. 1;

FIG. 6 is a right-side elevational view of the air fryer shown in FIG. 1;

FIG. 7 is a top elevational view of the air fryer shown in FIG. 1; and,

FIG. 8 is a bottom elevational view of the air fryer shown in FIG. 1.

The broken lines shown in the drawings are for the purpose of illustrating portions of the air fryer that form no part of the claimed design.
